UNITED STATES PATENT OFFICE.

HENRIETTA F. DUKE, OF NEW YORK, N. Y., ASSIGNOR TO THE BUTTERICK PUBLISHING COMPANY, (LIMITED,) OF SAME PLACE.

DESIGN FOR A LADY'S EVENING WAIST.

SPECIFICATION forming part of Design No. 17,956, dated December 20, 1887.

Application filed November 10, 1887. Serial No. 254,874. Term of patent 3½ years.

To all whom it may concern:

Be it known that I, HENRIETTA F. DUKE, of the city, county, and State of New York, have invented and produced a new and original Design for a Pattern of a Lady's Evening Waist; and I do hereby declare that the engraved prints accompanying this specification convey to any one accustomed to using paper patterns a clear understanding of how a garment made up by the pattern will appear.

The design shows close-fitting fronts that display a V-shaped neck; a plaited ornament along the neck at either side of the front; a plain ornament passing along the back and lower edges of each plaited ornament, and shaping a point at its lower back and either side of the front corner and an ornamental lap down the closing; a close-fitting back that exhibits an underfolded box-plait below the

waist-line of its center seam, and a pointed ornament that follows the outline of the neck and reaches nearly half-way to the waist-line; elbow-sleeves that exhibit an opening nearly to the top, and then covered reverse folding over from the edges of the opening. The lower outline describes a point at the center of the front, a high arch at the sides, and a short position at the back.

What I claim as my invention, and desire to secure by Letters Patent, is—

The design for a lady's evening waist, as shown in the engraved prints accompanying this specification.

HENRIETTA F. DUKE.
